NOZZLE

Application filed May 31, 1930. Serial No. 458,372.

This invention relates particularly to the type of nozzles used upon the ordinary garden hose for sprinkling water upon lawns and gardens.

5 It is the object of the invention to provide a nozzle of the character indicated that will be economical to manufacture, of few parts, simple in form and construction, quickly and easily assembled, and highly efficient in its 10 practical application.

In the drawings:

Figure 1 is a side elevation of a portion of a hose with our improved nozzle mounted thereon.

15 Figure 2 is an enlarged longitudinal section through a nozzle embodying our invention.

Figure 3 is a front elevation of the nozzle.

Figure 4 is a rear elevation of the nozzle.

20 Figure 5 is a perspective illustration of the nozzle in use, partly in section and part broken away.

In the embodiment of the invention herein disclosed we show at 1 the body of the nozzle, 25 this being merely an annular member threaded at 2 for engaging a hose and having an inwardly directed flange 3 formed on its forward end to form a circular opening 4.

At 5 we show a thin sheet-metal disc of 30 such size as to drop readily into the body 1 where it is held firmly against the flange 3 by a standard rubber washer 6 and the coupling 7 of hose 8 when the nozzle is screwed tightly into position.

35 The disc 5 is concavo-convex in form throughout its central portion lying within the confines of the opening 4, the convex side of the disc being directed inwardly toward the discharging water, the two sides being 40 indicated by the reference numerals 9 and 10 respectively. In the present case the whole central portion of the disc is pressed outwardly so as to enter the opening 4 as shown at 11, thereby forming an annular channel or 45 pocket 12 at the rear of the disc. In the center of the disc, and extending across its center, is formed an oblong rectangular slot as 13, the width and length of the slot being 50 in substantially the proportion of one to

three, and the area of the slot being substantially one-sixth of the area of the disc.

The form and proportion of the slot 13 relative to the size and conformation of the disc, and the size of the chamber immediately in the rear of the slot and defined by the enclosing washer 6, is highly important, and but little variation can be allowed if the best results are desired. The disposition of the slot 13 in the very center of the dished disc 55 and extending equally both ways from the center is an exceedingly important feature of the invention as will appear in view of the following explanation.

When the nozzle is in use water under 60 pressure bears equally against the entire inner face, or surface 10, of the disc. If the disc were flat the water would be discharged in a solid stream having a cross-sectional area equal to that of the slot 13, at least for 65 a little distance from the nozzle. But since the disc 5 is dished as described it results that the edges 14 are slightly in advance of the edges 15, at least throughout the major portion of their lengths, with the result that 70 the water discharging over edges 14 slightly in advance of the water discharged over edges 15, and with somewhat augmented velocity, impinges upon the main stream both from above and below as indicated by arrows 16, 75 thereby flattening the stream out into a plane lying at right angles to the long axis of the slot 13. This action is clearly shown in Figure 5 wherein the arrows 17 indicate the normal direction of flow of the water over 80 edges 15.

85 In order to secure the results as described above, it is necessary that the chamber immediately to the rear of the disc 5 be large enough to permit the water to enter the slot 90 13 freely from all sides. It has been found that the area of the opening defined by the washer 6 must be not less than five times the area of the slot so that the water will be fed as freely over the corners of the slot 95 as over the side and end edges. The forming of the pocket 12 around the slot 13 renders the action of the device positive and insures even feeding of the water through the slot under varying pressures. 100

It is to be understood, of course, that while we have herein shown and described but one specific embodiment of the invention, changes in form, construction, and method of assembly and operation may be made within the scope of the appended claim.

We claim:

10 A nozzle of the character described comprising a thin dished disc having an oblong slot formed therein and extending both ways from the center thereof, and means for mounting the same on the end of a hose with its dished face directed outwardly.
